UNITED STATES PATENT OFFICE.

WARD RAYMOND, OF EASTON, PENNSYLVANIA, ASSIGNOR TO PENNSYLVANIA PUMP AND COMPRESSOR COMPANY, OF EASTON, PENNSYLVANIA, A CORPORATION OF PENNSYLVANIA.

PILOT VALVE FOR COMPRESSOR REGULATORS.

Application filed May 31, 1927. Serial No. 195,401.

This invention relates to regulating means for compressors and in particular to a pilot valve of improved form used in connection therewith.

5 An object of the present invention is to provide a pilot valve for a compressor regulator having means to supply fluid to an unloading device when the pressure within the receiver exceeds a predetermined maximum and also when the compressor slows down or stops.

10 Another object of the present invention is to provide a pilot valve with two independent means for operating the valve to unload the compressor.

15 A still further object of the invention is to provide two independent pressure operated means for operating the valve to unload a compressor.

20 A feature of importance is that two independently operated means are adapted to act upon and open a pilot valve and supply fluid to operate a compressor unloader mechanism.

25 Another advantage of the present invention is that the unloading devices of any preferred type may be controlled through the same pilot valve so that the compressor may be unloaded when the receiver pressure exceeds a predetermined maximum and also when the speed of the compressor falls below a predetermined limit, due to failure of electric current or through other causes.

30 With these and other objects in view, my invention consists in the features of construction and operation set forth in the following specification and illustrated in the accompanying drawing.

35 In the accompanying drawing annexed hereto and forming a part of this specification, I have shown my invention applied to a pilot valve of preferred form, but it is to be understood that the invention can be otherwise embodied, and that the drawing is not to be construed as defining or limiting the scope of the invention, the claims appended to this specification being relied upon for that purpose.

40 In the drawing:
The figure is a central longitudinal section of a pilot valve made according to the present invention.

45 In the above mentioned drawing I have shown but one preferred embodiment of the

invention which is now deemed preferable, 55 but it is to be understood that changes and modifications may be made within the scope of the appended claims without departing from the spirit of the invention.

Briefly, and in its broadest aspect, my invention comprises the following principal parts: First, a body member; second, two fixed valve seats therein; third, a valve in the body member movable between said seats; fourth, a spring pressed rod normally holding the valve in one position; fifth, a spring preferably surrounding the rod; sixth, means to regulate the pressure exerted by said spring against said rod; seventh, manual means to move the rod against the pressure of said spring and permit movement of said valve; eighth, a second spring pressed rod adapted to be moved into contact with said valve; ninth, pressure means acting directly against said valve; and tenth, means to force said second rod against said valve to force said valve away from one of its seats.

50 Referring more in detail to the figure of the drawing, I provide a body member 10 with an opening 11 to which a conduit may be attached extending to unloading means for the compressor. As the unloading means may be of any usual or well-known type or types, it is not thought necessary to illustrate them. The body member 10 is also provided with a member 12 secured thereto by any preferred means. This member 12 is provided with an opening 14 adapted to receive a conduit adapted to be connected to the receiver (not shown) of a compressor, the pressure of which is to be controlled.

55 Within the body member 10 is provided a valve seat 15 which, as shown, is formed integrally in this body member. Another seat 16 is provided in the member 12. These valve seats 15 and 16 are oppositely disposed and so spaced apart that a valve 17 may move slightly between them. Surfaces are provided on the valve 17 at its opposite ends for contact with these seats 15 and 16.

60 Normally holding the valve 17 against one of the seats, 16 in the present instance, is a spring pressed rod 19, the upper end of which bears directly against the valve 17. To force this rod 19 upward to hold the valve 17 105 against the seat 16 is a spring 20, one end of which is suitably attached to the body member 10. The lower end of the spring engages

a nut 22. Nut 22 is internally threaded for an adjusting screw 23, the upper end of which engages the lower end of rod 20.

The above construction of pilot valve corresponds to that disclosed in my Patent 1,523,716 granted January 20, 1925. By varying the effective length of the spring 20 and the position of the screw 23 the pressure at which the valve 17 may open and also its sensitivity to variations of pressure may be regulated.

In addition to the operation of the pilot valve 17 directly by receiver pressure from opening 14 it is sometimes desirable to manually unload the compressor. A lever 27 is therefore provided suitably mounted on the body member 10 to force the rod 20 downward. A cam 29 having a handle thereon also mounted on the body member 10 is provided to oscillate the lever 29 and thus hold the rod 20 downward. With the rod 20 held downward in its lowermost position the valve 17 is free to open and admit receiver pressure from opening 14 to the opening 11 and thence to any desired unloading devices.

A third means to move valve 17 away from its seat 15 to unload the compressor is also provided. This means also may be automatically operated by pressure. Referring to the form shown in the figure, a diaphragm or other form of movable member 30 is mounted in an extension suitably formed on the member 12. The space above the diaphragm or movable member is adapted to be connected through an opening 31 to a conduit extending to a centrifugally controlled valve. This centrifugally controlled valve may be similar to that shown in my Patent 1,561,886, granted November 17, 1925. When the speed of the compressor is below normal or has not been brought up to normal when starting the compressor, pressure is supplied to the space above the diaphragm or movable member 30. This diaphragm or movable member is therefore forced downward and forces a rod 32 downward into contact with the upper surface of valve 17, thus moving valve 17 to its open position. As shown, the upper end of the rod 32 is attached to the center of the diaphragm and is guided and supported by a pressure-tight gland 33 of usual construction to prevent leakage of fluid from the space above the valve 17. Normally, also, the rod 32 is resiliently forced upward by a spring 34 surrounding the rod 32.

I claim as my invention:

1. A pilot valve for compressors comprising in combination, a body member having opposed valve seats therein, a valve adapted to be moved between said seats, spring means normally holding said valve against one of said seats, and a pressure operated means to move said valve toward its opposite seat, said valve also being movable by fluid under pressure against one of its faces.

2. A pilot valve for compressors comprising in combination, a body member having opposed valve seats therein, a valve adapted to be moved between said seats, spring means normally holding said valve against one of said seats, and a pressure operated means adapted to contact with one face of said valve and move said valve toward its opposite seat, said valve also being movable by fluid under pressure directly against said face. 75

3. A pilot valve for compressors comprising in combination, a body member having opposed valve seats therein, a valve adapted to be moved between said seats, spring means normally holding said valve against one of said seats, and a pressure operated means operated by fluid from one source to move said valve toward its opposite seat, said valve also being movable by fluid under pressure from another source against one of its faces. 85

4. A pilot valve for compressors comprising in combination, a body member having opposed valve seats therein, a valve adapted to be moved between said seats, spring means normally holding said valve against one of said seats, means to supply fluid under pressure against a face of said valve for moving said valve toward its opposite seat, a movable member mounted on said body member, means to supply fluid pressure against one side of said movable member, and means connecting said movable member whereby movement of said movable member in one direction will force said valve toward said opposite seat. 100

5. A pilot valve for compressors comprising in combination, a body member having opposed valve seats therein, a valve adapted to be moved between said seats, spring means normally holding said valve against one of said seats, means to supply fluid under pressure against a face of said valve and adapted to move said valve toward its opposite seat, a movable member mounted on said body member, resilient means normally holding said movable member in one direction, fluid pressure means to force said movable member in the opposite direction, and means connected to said movable member whereby movement of said movable member will force said valve toward said opposite seat. 110

6. A pilot valve for compressors comprising in combination, a body member having opposed valve seats therein, a valve adapted to be moved between said seats, spring means normally holding said valve against one of said seats, means to supply fluid under pressure against a face of said valve and adapted to move said valve toward its opposite seat, a flexible diaphragm mounted on said body member, resilient means normally holding said movable member in one direction, means to supply fluid under pressure against a face of said diaphragm to force said diaphragm in the opposite direction, and means con- 115

130

nected to said diaphragm whereby movement of said diaphragm will force said valve towards said opposite seat.

7. A pilot valve for compressors comprising in combination, a body member having opposed valve seats therein, a valve adapted to be moved between said seats, spring means normally holding said valve against one of said seats, means to supply fluid under pressure against a face of said valve to move said valve toward its opposite seat, means mov-

ably mounted on said body member and so related to said valve that movement of said last named means will force said valve toward said opposite seat, and fluid pressure means to operate said last named means independently of said first named fluid pressure means. 15

In testimony whereof, I hereto affix my signature.

WARD RAYMOND.
